UNITED STATES PATENT OFFICE.

JOHN C. VETTER, OF INDIANAPOLIS, INDIANA.

IMPROVEMENT IN LADIES' TOILET-CABINETS.

Specification forming part of Letters Patent No. 140,824, dated June 24, 1873; application filed May 10, 1873.

To all whom it may concern:

Be it known that I, JOHN C. VETTER, of the city of Indianapolis, in the county of Marion and the State of Indiana, have invented certain new and useful Improvements in Toilet-Cabinets, which have not heretofore been known or used, and that the following is a full and exact description of the construction and operation thereof, reference being had to the annexed drawings making a part of this specification and to the letters and figures of reference marked thereon.

Figure 1 indicates a front view of the cabinet. Fig. 2 is a representation of a vertical cross-section. Fig. 3 is a representation of a rear view. Figs. 4 and 5 are horizontal sectional views.

This invention has relation to certain improvements in toilet-cabinets for ladies' use; and it consists in the construction and novel arrangement, in connection with the cabinet, of a sewing-machine table, secretary, book-case, mirror, folding and sliding chair, and sliding cover to sewing-machine table, and other devices, in the manner hereinafter more fully described.

In the accompanying drawings, the letter A designates the frame of the cabinet, the lower portion of which consists of a casing, B, surmounted by a table-top, C, and the upper portion of which consists of the uprights D and the transverse boards E, connecting these uprights about midway of their height from the table-top. F indicates the base or bottom of the lower case B, preferably made similar in size and form to the table-top C, which is designed to be semicircular. The top C and bottom B are connected by the parallel plain partition-walls E' E'' extending from front to rear of the case on each side of the center, by the plain partition-wall G at right angles with the walls E' E'', and by the curved vertical side walls H. The side walls H are double, and have between them hollow chambers for the reception of the horizontally-sliding curved doors I when they are thrown open. The partition G divides the spaces between the partitions E' E'' into front and rear chambers. The front central chamber K is designed for the reception of the folding-chair, and the chamber K' on each side of it is provided

with a set of drawers, K''. The rear central chamber L should be provided with shelves L', and the chambers L'', at each side of the central chamber, with the weights a, by which the doors I are drawn back into the recesses of the curved side walls, pulleys b being arranged for the passage of the suspending-cords c, which extend across the tops of the chambers M, immediately under the table-top. The chambers M lie between the curved side walls and the plane walls E', opening to the rear. They may be provided with suitable shelving. These rear chambers are designed to be closed by means of doors N, hinged at the edge in the ordinary manner. The table-top C is suitably recessed or slotted at d for the reception of a sewing-machine. In rear of this slot the top is rectangularly recessed at e, to receive the back wall of the folding-cover P when folded down. This wall f is hinged to the table-top at the forward edge of this recess by its lower edge, and by its upper edge to the rear leaf g of the circular front wall h. Parallel with the side uprights D are arranged the inner vertical walls D', at each end of the table-cover P, the spaces between these walls and the end walls being occupied by sets of drawers, which may be fixed or hinged, as at k, in the set Q, to be swung around forward in such a manner as to expose the rear drawers l of the set. When those sets Q R of drawers are hinged, the walls D' form portions of their frames, and are not rigidly attached to the cabinet-frame. To the front edges of the walls D', whether fixed or movable, are hinged the sides S of the cover P. These sides are provided with narrow lips m on their front or curved edges n, designed to fit in suitable grooves v, in the front or curved walls of the table-cover. The transverse-board E is arranged with a suitable parallel-board, or with guide-strips to support a drawer, P', in which is packed a folding-desk, Z, consisting of two leaves, z' z'', hinged together, and the hinged standards n'. One of the leaves z' is hinged to the front wall of the drawer P'. Above the transverse board E is arranged centrally a pivoted mirror, Y, the journals of which are connected with the inside walls Q' of the book and pigeon-hole cases R'. These cases are provided with suitable doors y', and their tops r'

may be provided with edge-strips s'' , and serve as shelving for books or other articles. Z'' designates the folding-chair. Its pedestal consists of three legs, of which two, l' , are laterally located, and one, l'' , is placed in rear. The legs l' are hinged to a sliding base, a'' , grooved near the side edges on its upper surface for engagement with the guide-flanges b'' , which are secured to the wall of the chamber K . The rear leg l'' is jointed at c'' ; the folding end d'' being forked, usually, to secure a better foundation, when unfolded and resting on the floor. The seat e'' is pivoted to the pedestal, and is provided with a hinged or pivoted back, f'' , which is designed to be folded down on the seat when the latter is pushed into the chamber K . A small spring, g'' , is seated in the frame of the seat e'' , under the back f'' , to prevent rigidity, and give ease to the occupant. When the seat is not in use it is designed to be pushed back into the chamber K , the back f'' and the leg l'' being folded for this purpose. The doors of this chamber may then be drawn together and secured. The seat of this chair is designed to be elevated or depressed by means of a screw, n'' . A spring, m'' , is used to connect the folding end d'' to the seat of the chair, to keep it folded up close when not in use. The curved doors I are opened by pressing downward on the button of the vertical release-rod v'' , kept up, when not under pressure, by a spring. This action depresses the catch-springs x'' and releases the catches or shoulders w'' in the bottom or top of the doors, thereby allowing the weights to fall, drawing the doors back into their recesses. The left-hand case of drawers at the side of the table-top is preferably made to turn outward on hinges, as above described, in order to give room for the work when the sewing-machine is in operation.

What I claim as my invention, and desire to secure by Letters Patent, is—

1. The circular or segment-shaped cabinet-case, having the table-top C slotted at d and recessed at e , for the reception of a sewing-machine, and the chamber K with guides b'' for the reception of a folding and adjustable chair, Z'' , having the sliding base a'' , substantially as specified.

2. The combination, with the cabinet-chamber K having guides b'' , of the chair Z'' having the folding-back f'' , spring g'' , adjustable pivoted seat e'' , hinged legs l' , sliding base a'' , and folding rear leg l'' , substantially as specified.

3. The combination and arrangement, in the segment-shaped casing, of the curved sliding doors I , weights a , pulleys b , cords c , spring-catches x'' , hooks or shoulders w'' , and spring-release v'' , substantially as specified.

4. The cabinet having the hinged case Q turning outward, and bearing the folding sector-shaped side S , in connection with the sewing-machine table c , the folding-cover having the curved hinged wall h , and the opposite hinged sector-shaped side S , substantially as specified.

5. The drawer P' , and the folding-desk Z hinged to the front wall of said drawers, and provided with the folding-legs n' , adapted to rest when unfolded on the cover P , substantially as specified.

6. In connection with the cabinet-table top c , and the side supports $D D'$ extending upward therefrom, the hinged sector-shaped sides S' , beaded at m , and the folding-cover P , curved at h , said curved portion being grooved at v to fit the beads of the sector-shaped sides, substantially as specified.

Witnesses: JOHN C. VETTER.
